UNITED STATES PATENT OFFICE.

HAROLD G. WARR, OF PARK RIDGE, ILLINOIS, ASSIGNOR TO THE P & M COMPANY, OF CHICAGO, ILLINOIS, A CORPORATION OF ILLINOIS.

RAIL ANCHOR.

1,425,224.

Specification of Letters Patent. Patented Aug. 8, 1922.

Application filed July 2, 1920. Serial No. 393,595.

To all whom it may concern:

Be it known that I, HAROLD G. WARR, a citizen of the United States, residing at Park Ridge, in the county of Cook and State of Illinois, have invented certain new and useful Improvements in Rail Anchors, of which the following is a specification.

My invention relates to rail anchoring devices, and has for a primary object to provide an improved device of this character, adapted to be strained in its application to a rail, so that its initial grip will be maintained by spring action, which device may be manufactured with a substantial saving of material over devices of this general character now in use; which may be readily applied to rails having base flanges of different widths and thicknesses, and which when applied to such base flanges will normally stand at substantially right angles to the length of the rail, though with capacity to take a shackle hold on the rail base during the presence of a creeping pressure.

A further and more specific object is to provide an improved rail anchor of the general type in which a spring yoke member is subjected to a torsional or twisting strain, so as to grip the base flange of the rail with spring pressure, and thereby compensate for variations in the thickness of the base flanges of the rail, and also having a wedging engagement with a shoe or tie abutting member, so as to be adapted for use in connection with rails having base flanges of different widths. In this connection the invention contemplates a novel form of shoe member adapted to fit over one edge of the rail base, and a spring yoke member which engages the opposite edge of the rail base and interlocks with the shoe, the said yoke being so formed that when it is given a torsional strain in its application to the rail, it will exert a spring grip on opposite edges of the rail base, and the wedging engagement of the said shoe and yoke members being such that the anchor device may be applied to rails having base flanges of different width, so as to firmly grip the opposite vertical edges of such flanges, transversely of the rail, irrespective of the degree of torsional or twisting action to which the yoke member may be subjected.

The invention has for further objects the novel arrangements, constructions and combination of parts hereinafter more specifically described and claimed, for carrying out the above stated objects, and such other objects as will appear from the following description.

The invention is illustrated in certain preferred embodiments in the accompanying drawings, wherein—

Fig. 1 is a plan view of a rail anchor device constructed in accordance with the invention, showing the same applied in its operative position on the base flange of a rail.

Fig. 2 is an end view of the structure shown in Fig. 1.

Fig. 3 is a cross-sectional view taken on line 3—3 of Fig. 1.

Fig. 4 is a view in perspective of a modified form of yoke member employed in connection with another embodiment.

Fig. 5 is a view similar to Fig. 3, showing the modified form of yoke, illustrated in Fig. 4 in its applied position on the rail base, and in its interlocking position with a modified form of shoe member;

Fig. 6 is a side view in elevation of the yoke and shoe members, illustrated in Fig. 5, and showing the manner in which the yoke member is fitted over opposite edges of the rail base before it is interlocked with the shoe member.

Like characters of reference designate corresponding parts throughout the several figures of the drawings.

Referring first to Figs. 1 to 3, inclusive, of the drawings: 10 designates a railroad rail, and 11 one of the cross ties on which the rail is supported. The rail anchor illustrated in these figures is shown in its operative position on the base flange of the rail, and preferably comprises a shoe member 12 which fits over one edge of the base flange of the rail, and a spring yoke member 13 which engages the opposite edge of the base flange and extends around the outer face of the shoe member. The shoe member is preferably angular in cross-section, consisting of an upper lip 14, which extends the full length of the shoe and bears upon the upper inclined surface of the rail base, and a vertical web 15 which engages with

one of the vertical edges of the said base. The shoe is provided at its forward end with a tie-abutting flange 16, adapted to bear against one of the vertical faces of the cross-tie 11, and is also provided at this end with a laterally projecting flange 17 which extends under the base of the rail at a point adjacent the tie. The web portion 15 of the shoe increases in thickness toward the tie-abutting flange, so as to provide a wedge surface which intervenes between the edge of the rail and one end of the spring yoke 13. A plurality of notches 18 are formed on the upper surface of the shoe and are engaged by a portion of the yoke member, as will be hereinafter more specifically described, so as to lock the yoke in its operative position. The yoke member is preferably made of spring metal, and is formed at one end with a hook providing a recess 19, which fits over the edge of the rail base at a point opposite the shoe, the lip 20 of said hook being bent toward the tie, so that it will stand at an angle with relation to the body of the yoke. The other end of the yoke is formed with a hooked portion 21 which fits over the wedge 15 of the shoe and is formed with a laterally projecting lip 22 which interlocks with the notches 18 of the shoe when the yoke is in its operative position. The body portion of the yoke, which extends under the rail, is given a torsional or twisted set, so that the hooks at opposite ends of the yoke will normally stand at an angle to each other so as to require the yoke to be subjected to a torsional strain when it is fitted over the shoe member.

The anchor device above described may be applied to the rail by first slipping the shoe 12 over one edge of the rail base at a point where the foot 16 will bear against the tie 11. The hook 20 of the spring yoke is then fitted over the opposite edge of the rail base, and the yoke subjected to a twisting strain, as by twisting the hooked portion 21 in a direction toward the tie. When the yoke is strained in this manner, the lip 22 may be readily passed over the rear end of the shoe to its desired interlocking position. The spring tension resulting from the torsional or twisting action of the anchor during its application to the rail causes the edge of the angular lip 20 to bear with spring pressure against the upper inclined surface of the rail base, and likewise causes the lip 22 of the hooked portion 21 to exert a downward pressure on the shoe member. This spring tension of the yoke operates to hold the lip 14 of the shoe in tight frictional engagement with the upper surface of the rail, and also prevents the anchor device from being loosened by the vibration of the rail or other disturbing causes. After the above preliminary engagement has been effected between the yoke and the shoe mem-

bers, the yoke member may be moved forward on the wedge 15 of the shoe, so as to effect a firm transverse grip of the device on the rail base. By providing the shoe with the wedge surface 15, the anchor may be applied to rails having base flanges differing in width, and permit the yoke member under such conditions to be normally maintained in a position at substantially right angles to the length of the rail, where by a slight creeping movement of the rail will cause the device to take a firm shackle hold on the rail. By providing a spring yoke member with a hook which fits over the shoe, in the manner disclosed in the above figures of the drawings, it is possible to make the shoe member much lighter than is practicable with the shoe members of other types of devices of this general character.

In Figs. 4 to 6 inclusive, a modified form of rail anchor is shown, in which the hook portion adapted to fit over the shoe overlaps the edge of the rail base. This modification consists of a shoe member 12^a which is formed substantially the same as the shoe member 12 shown in the preceding figures, with the exception that it is not provided with notches, as shown in Figs. 1, 2 and 3. The yoke member 13^a of the modification is substantially the same as the yoke 13 shown in Figs. 1, 2 and 3, with the exception that the hooked end 21^a is provided with a relatively long lip 22^a, so that this lip will overlap the edge of the rail base and exert a firm spring pressure on the lip 14^a of the shoe 12^a. With this construction it is unnecessary for the shoe member 12^a to be made so as to accurately fit the base flange of the rail, as the spring tension of the yoke will hold the lip 14^a in tight frictional engagement with the rail base, even though the distance between said lip 14^a and the lower lip 17^a be somewhat greater than the thickness of the rail base flange.

The spring yoke 13^a is applied to the rail by fitting the hook end 21^a over one edge of the rail base, as shown in Fig. 6, so as to permit the hook 20^a to clear the opposite edge of the rail. The hooked end 20^a may then be raised so that the hooked portion can be fitted onto the rail base by moving the yoke laterally to the left. The lip 22^a of the hooked end 21^a may then be forced over the shoe member, and the yoke forced up on the wedge surface 15^a of the shoe, in substantially the same manner as that described in connection with the description of Figs. 1 to 3 inclusive.

While the invention has been illustrated in two specific embodiments, it will be obvious that further modifications might be made without departure from the invention. It will therefore be understood that the invention is not limited to the structures shown

and described, except in so far as specific limitations may appear in the appended claims.

I claim:

1. A rail anchor comprising rail base embracing members, one being a spring adapted to exert spring pressure on the upper and lower surfaces of said rail base adjacent opposite edges thereof, which members are capable of different engagements with each other to accommodate the anchor to rail bases of differing contour. 70
2. A rail anchor comprising rail base embracing members, one being a spring adapted to exert spring pressure on said rail base adjacent opposite edges thereof, which members are capable of different engagements with each other to accommodate the anchor to rail bases of different width and thickness. 75
3. A rail anchor comprising rail base embracing members, one being a spring adapted to exert spring pressure on said rail base adjacent opposite edges thereof, which members are capable of different interlocking engagements with each other to accommodate the anchor to rail bases of different width and thickness. 80
4. A rail anchor comprising a shoe having a jaw adapted to fit over one edge of the base flange of a rail, and a spring member having a jaw at one end adapted to engage with the opposite edge of said base flange, and formed at the other end with a jaw having a recess adapted to fit over the shoe, said spring member being adapted to be strained in its application to the rail so as to exert spring pressure on opposite edges of the rail base. 85
5. A rail anchor comprising a shoe having a jaw adapted to fit over one edge of the base flange of a rail, and a spring member having a jaw at one end adapted to engage with the opposite edge of said rail base and formed at the other end with a jaw adapted to fit over said shoe; said spring being adapted to increase its hold on the rail during the presence of a creeping pressure and to be strained in its application to the rail, so as to exert spring pressure on opposite edges of the rail base. 90
6. A rail anchor comprising a shoe having a jaw adapted to fit over one edge of the base flange of a rail, and a spring member having a jaw at one end adapted to engage with the opposite edge of said base flange and formed at the other end with a jaw adapted to fit over said shoe; said spring member being adapted to take a shackle hold on the rail during the presence of a creeping pressure and to be strained in its application to the rail so as to exert spring pressure on opposite edges of the rail base. 95
7. A rail anchor comprising a shoe having a jaw adapted to fit over one edge of the base flange of a rail, and a spring member adapted to engage the opposite edge of said 100
8. A rail anchor comprising a member adapted to engage one edge of the base flange of a rail, and a spring member adapted to engage the opposite edge of the rail base and to engage with said member; said members having a wedging engagement with each other whereby the anchor will fit rail bases of differing width and said spring member being strained in its application to the rail so as to exert spring pressure on opposite edges of said base. 105
9. A rail anchor comprising a member adapted to engage with one edge of the base flange of a rail, and a member having a wedging engagement with said first mentioned member, one of said members being a spring adapted to be strained in its application to the rail whereby a spring grip is exerted against the said base and said other member adjacent one edge of said base. 110
10. A rail anchor comprising a member adapted to engage with one edge of the base flange of a rail, and a yoke member having a wedging engagement with said first-mentioned member, one of said members being a spring adapted to be strained in its application to the rail whereby a spring grip is exerted against the said base and said other member adjacent one edge of said base. 115
11. A rail anchor comprising a member adapted to engage with one edge of the base flange of a rail, and a yoke member having a wedging engagement with said first-mentioned member and adapted to bear with spring pressure on the upper surface of said other member. 120
12. A rail anchor comprising a shoe adapted to engage with one edge of a rail base, and a spring member provided at one end with a jaw for engagement with the opposite edge of the rail base and at its other end with a hook adapted to fit over the shoe member, the said hook being provided with a lip adapted to extend over the upper surface of the shoe and engage the same with spring pressure. 125
13. A rail anchor comprising a shoe adapted to engage with one edge of a rail base, and a spring member provided at one end with a jaw for engagement with the opposite edge of the rail base and at its other end with a hook adapted to fit over the shoe member, the said hook being provided with a lip adapted to extend over the upper surface of the shoe and engage the same with spring pressure. 130
14. A rail anchor comprising a shoe adapted to engage with one edge of a rail base, and a spring yoke adapted to engage the opposite edge of said base and provided with a hook which is strained into operative engagement

- with the upper surface of the shoe; said shoe being formed with a wedge intervening between said hook portion and the rail base whereby the anchor may be adjusted to grip rail bases of differing width.
15. A rail anchor comprising a shoe adapted to engage with one edge of a rail base and abut against a cross tie and a spring yoke adapted to engage the opposite edge of said base and provided with a hook which is strained into operative engagement with the upper surface of the shoe; said shoe being formed with a wedge intervening between said hook portion and the rail base whereby the anchor may be adjusted to grip rail bases of differing width.
16. A rail anchor comprising a shoe member adapted to engage with one edge of a rail base and a spring yoke member adapted to engage the opposite edge of said base and formed with a hook adapted to engage with the upper surface of the shoe, one of said members being provided with a tie abutment and the yoke member being subjected to a torsional strain in its application to the rail.
17. A rail anchor comprising a shoe member adapted to engage with one edge of a rail base and formed with a wedge portion and a spring yoke member adapted to engage the opposite edge of said base and formed with a hook adapted to engage with the upper surface of the shoe, one of said members being provided with a tie abutment and the yoke member being subjected to a torsional strain in its application to the rail.
18. A rail anchor comprising a wedge member adapted to engage with one edge of a rail base and a spring yoke member adapted to engage the opposite edge of said base and formed with a hook adapted to interlock with the upper surface of said wedge, one of said members being provided with a tie abutment and the spring member being subjected to a torsional strain in its application to the rail.
19. A rail anchor comprising a wedge member adapted to engage with one edge of a rail base and formed on its upper surface with notches and a spring yoke member adapted to engage the opposite edge of said base and formed with a hook adapted to interlock with said notches, one of said members being provided with a tie abutment and the spring member being subjected to a torsional strain in its application to the rail.

HAROLD G. WARR.
